POCKET ATOMIZER

John Holtzman, New York, N. Y.

Application March 7, 1931, Serial No. 520,988

3 Claims. (Cl. 299—88)

This invention relates to atomizers adapted to be carried about the person of the user.

Fig. 1 is a vertical section of my improved atomizer, taken on the line 1—1 of Fig. 2.

5 Fig. 2 is a top plan view of the same.

Fig. 3 is a horizontal section of the same, taken on the line 3—3 of Fig. 1.

In the practical embodiment of my invention, the means for locking the plunger 150 of the 10 atomizer may also be used to rotate the atomizer cover 162 and pipe sealing means 28 carried by the cover, out of the way so that the atomizing operation may be performed. Toward this end, the plunger 150 is preferably made of non-circular cross-section and is provided with a recess 151 for the reception of the locking edge 152. Said locking edge forms one wall of an aperture as 153 in a suitable slide as 154 mounted on the top 155 of the casing 10. The slide 154 terminates in a suitable enlarged finger piece 156 which passes through a suitable aperture in the casing wall and projects sufficiently for manual operation thereof by the finger of the user. The slide 154 is normally pressed outwardly by means of 15 the leaf spring 157 which is secured at one end to said slide as at 158, the other end 159 thereof being free and engaging the shaft 160. Said shaft is pivoted in the upstanding walls 161 of the casing 10 and pivotally supports one end of the 20 cover 162. At its other end, the cover is provided with a depending wall 163 adapted to close the aperture 164 in the casing wall. The bent locking spring 165 secured to the cover is adapted to enter said aperture 164 for retaining the cover 25 removably in its normal position. The means for atomizing the perfume in the casing 10 is well known and hence need not be described at great length. Suffice it to say that a suitable cylindrical pump compartment or cylinder as 39 is provided in the casing 10, which compartment is closed at its lower end by a suitable screw plug threaded to the lower end of the cylinder. The usual piston with its air valves is provided on the plunger 150 and snugly fits inside the wall 30 of the cylinder 39. The upper end of the cylinder 39 is closed by a suitable removable screw plug which also serves as a guide for the plunger. From the lower end of the cylinder, the pipe 43 leads toward the upper end of the liquid pipe 27, the latter pipe being open at its lower end and constricted at its upper end.

It will be seen that as the slide 154 is pressed inwardly against the action of the spring 157, the end 166 of said slide engages the inclined edge 55 167 of the cover and rotates said cover about its

pivot 160, thereby removing the spring 165 from the aperture 164 and removing the closure screw 28 from the pipe 27. At the same time, the edge 152 is withdrawn from the recess 151 whereby the plunger 150 is released and is moved upwardly by the spring 35.

It will be understood that the cover 162 is frictionally retained in its open position when moved into said position by the slide, and that movement of the cover out of its sealing position is also resisted by the spring 157 which is secured to and is virtually an extension of the slide. This is done by securing said cover to the shaft 160 and depending on the friction of said shaft against the spring 157 to retain the shaft in the 15 position into which it is rotated. After the plunger has been raised under the influence of the spring 35, said plunger may be reciprocated to perform the atomizing operation as by means of the finger piece 156 secured thereto. It may 20 then readily be locked by moving it into its lowermost position whereupon the slide will snap into the recess 151 and lock the plunger. The cover 162 may then be rotated manually into its closed position wherein the spring 165 snaps 25 against the edge of the aperture 164 and retains the cover in place until again released by the manual operation of the slide 154, the spring 157 aiding to resist movement of the cover.

While I have shown and described certain 30 specific embodiments of my invention, it will be understood that I do not intend to limit myself thereto but intend to claim my invention as broadly as may be permitted by the state of the prior art and the scope of the appended claims. 35

I claim:

1. In an article of the character described, a casing, atomizing means within the casing including an outwardly spring-pressed reciprocating member operable from the exterior of the 40 casing and having a transverse groove therein, a sealing cover arranged to seal said atomizing means and having a pivot connecting the cover to the casing, said cover having a beveled end edge in spaced relation to the pivot, a locking 45 slide in the casing having an end portion projecting therefrom outside of the casing, part of said slide entering said groove for normally locking the reciprocating member, said slide engaging a point of the beveled end edge of the sealing cover in spaced relation to the pivot when said slide part is moved out of said groove to rotate the cover about said pivot into position to unseal said means and simultaneously to release the reciprocating member. 50 55 56

2. In an atomizer, a casing, atomizing means within the casing including a reciprocatory pump plunger having a part thereof accessible from outside the casing and having a transverse locking groove therein, a spring urging said plunger outwardly of the casing, and a discharge pipe for atomized fluid, a cover pivoted to the casing and having an end thereon, a plug carried by the cover in position to seal said pipe, a spring latch carried by the cover and normally engaging the casing, a plunger-locking and cover-opening slide carried by and accessible from outside the casing and having an end thereon, said end engaging the end of the cover when the slide is moved to swing said cover about its pivot, and a spring normally urging the slide into the groove of said plunger to lock the plunger, said plunger being unlocked on the cover-opening movement of the slide.
3. In an atomizer, a casing, means for atomizing fluid within the casing, said atomizing means including a reciprocatory air-pump piston-plunger, said plunger having a transverse groove therein, a spring urging said plunger in one direction and out of the casing, said plunger being manually operable in the other direction against the action of the spring to produce a stream of fluid-atomizing air, and a discharge pipe, a cover having a pivot hinging the cover to

the casing and having means thereon for sealing said discharge pipe, said cover having an inner end within the casing, spring means on said cover arranged to frictionally engage the casing to maintain said cover normally in pipe sealing position, said spring means, on disengagement from the casing, releasing said cover for swinging movement about its pivot, a manually operable spring-pressed plunger-locking and cover-opening slide mounted for manual reciprocatory movement transversely of the casing and arranged with the larger part thereof inside of the casing, said slide having an opening therein through which the plunger is slidably passed, the wall of the slide adjacent said opening entering the groove of the plunger when said slide is moved in one direction, the inner end of the slide being arranged adjacent the inner end of the cover and below the pivot of the cover, said inner end of the slide engaging said inner end of the cover on movement of the slide in the other direction and on said movement swinging the cover about its pivot and first releasing the spring means from the casing and then opening the cover while simultaneously withdrawing the slide from the groove of the plunger and freeing the plunger for movement out of the casing by said first-mentioned spring.

JOHN HOLTZMAN.
